F. A. FULLER

RAZOR STROPPING DEVICE

Filed March 6, 1919

Fig. 3.

INVENTOR.
F. A. FULLER.
FRED C. FISCHER.
ATTY.

UNITED STATES PATENT OFFICE.

FRANZ A. FULLER, OF NEWARK, NEW JERSEY.

RAZOR-STROPPING DEVICE.

Application filed March 6, 1919. Serial No. 280,982.

To all whom it may concern:

Be it known that I, FRANZ A. FULLER, a citizen of the United States, residing in the city of Newark, in the county of Essex 5 and State of New Jersey, have invented certain new and useful Improvements in Razor-Stropping Devices, of which the following is a full, clear, and exact description, such as will enable others skilled in the art to which it pertains to make, construct, and use the same, reference being had to the accompanying drawings, and to numerals of reference marked thereon, forming a part of this specification.

15 This invention relates to improvements in stropping devices, and more particularly to such as are adapted especially for stropping safety razor blades.

My invention has for its object, the production of a stropping device for safety razor blades having a frame adapted to slide longitudinally of a strop, a blade holder being pivotally supported in said frame, and means for rocking the blade holder and 25 blade for stropping the edge in such a manner as to positively prevent the blade from cutting or injuring the strop.

Further objects of the invention are to increase the simplicity of construction and 30 operation of the device by decreasing the number of parts of which the usual stropping device is composed; by lessening or avoiding the necessity of adjustment of the various parts and by increasing the manipulation of the device. To this end I have made many changes in this device from similar devices; all with the object of increased efficiency.

With these ends in view, my invention 40 consists of certain novelties of construction and arrangements of parts as hereinafter set forth and pointed out in the claim. While the preferred form of my invention is illustrated in the accompanying drawings, yet it is to be understood that minor changes may be made without departing from the scope thereof.

In the drawings in which like numerals 50 of reference indicate corresponding parts throughout,

Fig. 1 represents a side elevation of my improved device, partly broken away and partly in section, illustrating the manner in which the device is to be used for stropping the blade, and illustrating the cutting

edge of the blade in neutral relation to the strop.

Fig. 2 represents a rear elevation of my device, and

Fig. 3 represents a plan view of the frame holder.

In the drawings, 1 represents the body or frame of my improved stropping device, which body or frame may be stamped from sheet metal or the like, and afterwards bent 65 into the desired shape as shown. Said body or frame is made from a single piece of suitable material and comprises two opposite side portions 2 and 3 parallel each to each and connected by, preferably a straight 70 body portion 4. The front and rear longitudinal edges of the body or frame are preferably bent upwardly to provide bearing or guiding surfaces 5—5 for the strop. The body portion 4 of the frame 1 is provided with a pair of integral downwardly extending apertured lugs 6—6 preferably struck out from said body portion 4 and by means of which the said body or frame 1 is pivotally connected to the apertured lugs 7—7 80 of the handle 9, by means of the rivets 8—8.

The handle 9 may be stamped from sheet metal or the like and afterwards bent into the desired shape as shown. Said handle is made from a suitable piece of suitable 85 material and comprises two opposite side portions 10—10 parallel each to each, and connected by an upper cross piece 11 from which extend the integral oppositely arranged lugs 7—7. Journaled in the side 90 portions 2 and 3 of the body or frame 1 is a cylindrical rod or shaft 12, and a roller 13 to be engaged by the strop when the device is used for stropping the blade, as clearly indicated in Fig. 1 of the drawings.

The top rod or shaft 12 carries the blade holder 14 which holder may consist of a piece of sheet metal wrapped around said rod or shaft 12 and secured thereto in any convenient manner, so as to provide resilient clamping jaws 15—15 to receive the razor blade 16 as has been common in general heretofore. One of the jaws 15 is preferably provided with an integral lug 17 which is adapted to be engaged by the razor blade to limit the forward movement thereof. The side portions 2 and 3 have upper and lower holes forming bearings for the ends of the cylindrical rod or shaft 12 and the roller 13, both extending transversely 105 110

of the blade holder. The rod or shaft 12 and roller 13 are connected by means of pinions or gears 18-18, so that drawing the device along the strop will tend to turn the upper rod or shaft 12 carrying the blade holder 14, and when the direction of sliding the device is reversed, the said upper rod or shaft 12 will be turned over according to the principles already well understood in the art. The manner of pivotally and yieldingly connecting the body or frame 1 of the device with the handle, as above described, provides positive means for preventing the cutting edge of the blade from cutting or gouging the strop during the stropping operation.

The operation of the device is as follows: A safety razor blade is inserted between the resilient clamping jaws 15-15 of the blade holder 14; the strop 18 is then passed over the bearing or guiding surface 5 at one end of the frame 1, through the said frame and under the roller 13, and then out through and over the bearing or guiding surface 5 at the other end of the frame 1 of the device, as clearly indicated in Fig. 1 of the drawings.

The attaching end of the strop (not shown) is hooked over any stropping support, while its upper end (likewise not shown) is held in one hand. The other hand grips the handle 9 of the device and reciprocates said device back and forth along the strop thereby permitting the edge of the blade to be engaged with the strop. The present invention provides a very efficient and exceedingly simple and inexpensive stropping device, the same being constructed of a minimum number of parts, which are of such shape as to lend themselves readily to manufacture by the use of suitable punches and dies from ordinary sheet metal, and which parts are reduced to the simplest operative efficiency; and further, the invention provides a safety razor stropping device in which the accidental cutting or injuring of the strop and blade is posi-

tively prevented. The forward and backward movement of the body or frame 1 is limited by the body portion 4 thereof, engaging with either of the longitudinal edges or corners 19-19, of the cross piece 11 of the handle 9 which engagement limits the movement of the frame 1 in either direction.

Experience has demonstrated that the organization above described is a highly efficient one, and while I have shown the preferred embodiment of my present invention, I do not wish to be limited to the exact details of construction shown and described, as obvious modifications thereof, not involving the exercise of invention, may be made by any skilled mechanic, and such departures from what is herein set forth, I consider within the scope and terms of my claim.

I claim:—

A razor stropping device comprising a frame made from a single piece of suitable sheet material adapted to slide longitudinally of a strop, said frame comprising a body portion and two opposite side portions parallel each to each, said body portion being provided with an upwardly struck strengthening rib or bead at each edge and a pair of integral downwardly extending apertured lugs, a handle made from a single piece of suitable sheet material, said handle comprising two opposite side portions parallel each to each and connected by an upper cross-piece having backwardly struck ears lapped by said lugs and pivotally connected to said lugs so that the said upper cross-face of the handle engages with the under part of the body portion of the frame for limiting the movement of the frame.

This specification signed and witnessed this 4th day of March, 1919.

FRANZ A. FULLER.
